UNITED STATES PATENT OFFICE.

CHARLES FIELD YARDLEY, OF LARCHMONT, NEW YORK.

RAIL ANCHOR.

Application filed April 20, 1927. Serial No. 185,084.

The present invention relates to rail anchors or anti-creepers and is directed to the production of an improved one-piece type adapted to possess important advantages 5 with respect to simplified application and increased efficiency as compared with the structures as heretofore made.

A particular purpose of my present improvements is to produce an advantageous 10 form of rail anchor which will formatively allow of successfully meeting the severe conditions of advanced rail anchor design as to facility of application, rigid economy of manufacture and material and which in 15 its installation will have a constantly maintained resilient grip upon the rail and will be progressively tightened by the forces which cause the creeping of the rail.

The improved device of the present disclosure is generally of the type of one-piece rail anchor, as shown in my prior Patent No. 1,484,102 of February 19, 1924, comprising a bar or body portion having jaws at its opposite ends adapted to engage the 20 flanges at the opposite sides of a rail and wherein a substantial degree of gripping effect or pressure is obtained from a tightening action resulting from torsional displacement of the body of the anchor member.

An important feature of the present improvements consists of an improved form of the body or connecting portion which may preferably be in the form of a simple bend 35 therein positioned at a point underlying the rail base flange and desirably to one side of the rail web. As a result thereof, a portion of the body member together with the jaw integral therewith is displaced angularly or 40 longitudinally with relation to the rail and thereby to obtain a bearing contact between the anchor and the rail operative to maintain the related end of the anchor rigidly in vertical position and to relatively shorten 45 the length of the body portion subjected to distortion. The angular displacement of a portion of the body portion, together with its associated jaw, is of particular value in the illustrated type of anchor, first, in its provision for obtaining an improved degree 50 of vertical rigidity at one end of the anchor, while employing a jaw of relatively reduced size and simplified form, and in consequence, effecting a saving of metal; further in providing for obtaining a materially increased holding pressure on the rail by

confining the torsional displacement within a shorter length of the body portion of the anchor, and further contributing to the effectiveness of the anchor in allowing for initially increased angular relation of the body portion with respect to the longitudinal axis of the rail from which it results in conjunction with the specific form of jaw employed, that the maximum holding pressures are obtainable before the body assumes a position transversely of or perpendicular to the longitudinal axis of the rail. 60 65

My improved device is further designed to incorporate further features of improvement, including an improved form of jaw 70 formed to allow of the important advantage of applying the device to a rail without requiring the use of a special tool therefor, the same being permitted by the simple 75 operation of driving the jaw into effective position upon the rail and to produce the required torsional displacement of the body by means of a track maul or hammer.

The foregoing and other important features and advantages of the present invention will be more fully understood by reference to the accompanying drawings, wherein an approved embodiment of the features of my invention is illustrated, and wherein like 80 reference characters are applied to the corresponding parts in the several views. 85

In the drawings,

Figure 1 is a top plan view showing a rail anchor made in accordance with a preferred 90 form, and is shown applied to the base of a rail in operating position, having bearing contact with the tie to resist creeping of the rail;

Fig. 2 is a view thereof in front elevation; 95

Figs. 3 and 4, respectively, are views in front elevation and top plan of a simple modification of the form and design of the preceding figures;

Fig. 5 is a top plan view of a modified 100 construction employing a right-hand jaw of a modified form;

Fig. 6 is a view in front elevation of a further modified form having a right-hand jaw provided with a depending shoulder for 105 engagement with the rail flange;

Fig. 7 is a plan view thereof;

Fig. 8 is a further desirable modification generally similar to the preceding, but wherein the jaw is provided with a tapered 110 or beveled entry surface to facilitate installation;

Fig. 9 is a perspective view illustrating the blank of the form of device shown in Fig. 8;

Fig. 10 is a plan view of a simple modification of the form first illustrated; and

Figs. 11 and 12 are respectively front elevation and plan views of a further modification.

In the preferred form and as illustrated 10 in Figs. 1 and 2, the device is formed of a single piece of heavy sheet steel so proportioned and of such gauge that the body is of substantial strength and adapted to produce a substantial gripping pressure upon 15 the rail when placed under resiliently twisted condition or torque.

As shown, the connecting portion of the body is indicated at 1, and is positioned to underlie the rail flange in general transverse relation thereto, and is formed at its 20 end portions with oppositely positioned inwardly extended jaws 4 and 6, arranged to overlie the rail base flange and to have gripping engagement with the inclined upper surfaces thereof. As will be readily understood, the device is applied to the rail by placing the body portion 1 to cross the bottom face of the rail with the jaw 4 overlying the edge of the rail base flange and with 25 the shoulder portion indicated at 5 engaging the edge of the rail flange.

The spaced relation of the jaw 6 to the shoulder 5 and associated jaw 4, is such that the distance to the innermost end of the jaw 6 is less than the width of the rail base, and in consequence, in applying the anchor to the rail the right-hand end, as shown, is initially tilted downwardly and the jaw 6 is lifted by a suitable tool and sprung forwardly to clear the edge of the rail and to finally assume its position, as indicated, bearing upon the upper surface of the rail flange. In the operation of lifting the jaw 6 on to the rail flange, the straight body 40 portion of the bar will assume a relatively wide angular relation to the transverse axis of the rail, and further, will be given a resilient twist or torsional displacement, producing an initial resilient hold upon the rail flange. Thereafter, upon driving of the right-hand end portion toward the tie, as shown at 2, the bearing surface of the jaw 6 will be forced to ride inwardly upon the upward surface incline of the rail flange, and 45 in consequence, will increase the degree of torsional effect and resultant gripping action. In so far as described, the form and general application of the device to the rail corresponds in general to the disclosure of my prior patent hereinbefore referred to.

In accordance with an important feature of the present invention the body portion of the anchor at one end, at the left as here shown, is bent into angular displacement 50 with relation to the remaining or right-hand

end portion of the body, as indicated at 3. The angularly disposed portion of the body 3, thereby provides for a longitudinal extension of its bearing contact with the under side of the rail base at 3', which in conjunction with the engagement of the jaw 4, will operate to rigidly secure this end of the anchor in fixed vertical position and against tilting, and in consequence, effect the required securing of the one end of the anchor 75 necessary to set up the torsional twist at the opposite end of the body portion upon the raising or lifting of the jaw 6 upon and under the action of the incline of the rail base flange. The securing of the one end portion 80 of the bar against tilting from the vertical is accordingly accomplished by the simple bending operation without the provision of additional metal to effect the result. In addition thereto, the angularly disposed portion of the body 3 provides for the desirable increase in the angularity of the major body portion conducive to obtaining a more effective tightening action, and, moreover, confines the torsional displacement of the bar to 85 a reduced and limited section of the body, i. e., the straight body portion 1, as shown, whereby a substantially increased torsional pressure is obtained under the action of the jaw 6 riding inwardly upon the inclined surface of the rail base flange. 95

As best shown in Fig. 2, in the stamping out of the blank, to provide the simple form of the jaw 4 with the shoulder 5 for engaging the edge of the rail flange, the body portion at 11 may be slightly cut away adjacent the rail flange edge to provide for clearance desirable in the application of the anchor to the rail. The jaw 4 may also, and as shown, be left in parallel relation with the associated portion of the body during the bending operation whereby in its position of installation it will be angularly disposed to the rail, with the advantage that the edge of the shoulder portion 5 will bear against the rail edge to oppose the gripping action. The blank form of the jaw 6 is indicated by dotted lines in Fig. 2, and as shown, this jaw is turned inwardly from the blank form to provide an upwardly extending and inwardly directed shoulder portion 12 positioned to engage the edge of the rail base flange and the jaw 6 may desirably have its upward edge portion 13 rounded off in the manner as indicated. 115

In the modified form of the device, as illustrated in Fig. 3, the construction conforms to the preceding, with the exception of the form of the jaw 6, which, as shown, is formed with its end portion tapered or 120 rounded off at its under side at 14, thereby providing an inclined surface adapted to engage the edge of the rail flange and to ride upwardly thereon upon moving this end of the bar or anchor toward the trans- 130

verse position, whereby this modified structure upon properly spacing the jaw 6 with relation to the opposite jaw and with respect to the width of the rail, will allow of the device being applied by simply placing in position, and driving the jaw 6 end of the device toward the tie by means of a spike maul.

As will be appreciated, the features of my present invention may be embodied in varied form and arrangement without departing from the scope of the invention, and as illustrative thereof, I have shown in the remaining figures various modifications which may be made therein with advantages incident to the further improvements thereof, as shown.

In Fig. 4 there is shown a further modification of the design of the right-hand end of the anchor wherein the return bend 15 of the bar for turning inwardly of the jaw 6 is formed to occur partially underlying of the rail flange and thereby determining the position of the shoulder 12' to engage the edge of the rail flange at the inner edge thereof, and in advance of the position of corresponding engagement of Fig. 1.

In Fig. 5 the right-hand jaw is shown of the type indicated in Fig. 1 of my prior patent hereinbefore referred to, wherein the jaw is formed from an inwardly extended portion of the blank turned into angular position.

In Figs. 6 and 7 there is shown a further modified structure wherein the left hand jaw 4' corresponds in form to the previous disclosures, but is, as shown, bent with relation to the angular portion of the body to be in substantially parallel relation to the face of the tie. The opposite jaw 6' is of a modified form, bent from the inwardly extending portion of the blank and formed to provide a gripping and tightening jaw of the form to be lifted into engagement with the top surface of the rail flange, and having a depending shoulder portion 17, as indicated and arranged to effect engagement with the edge of the rail base flange, the jaw end being formed with a cut-away portion 18 below said shoulder, providing clearance and for the purpose of forming the jaw for bending with relation to the body portion of the anchor.

In Figs. 8 and 9, there is shown a modified structure generally similar to the preceding but wherein the jaw 6' is formed with a rounded or inclined outer and lower edge 19, adapting this form of jaw for application to the rail flange without special tool, the installation being effected by driving of the jaw 6' end of the device from extreme angular position toward transverse position. In the latter structure it will be understood that the spacing of the opposite jaws is such as to clear the rail base flange in the initial application of the device thereto.

In Figs. 10 and 11, the right-hand jaw end is of a modified form comprising a simple form of upwardly positioned hooked jaw 6'' initially outwardly projecting from the blank and turned inwardly into engaging position and having a depending rail flange edge engaging shoulder 20 formed as a part thereof and adapted to have engagement with the rail in an advanced position with relation to the main body of the anchor, as indicated. The extreme outer end of the jaw 6'', as indicated, is rounded off at its under edge to allow of installation by driving of the anchor toward the tie in the manner as hereinbefore described.

Fig. 12, here is shown an anchor in a modified form having the right-hand jaw formed with a return bend and with a shoulder 21 for engaging the rail base edge rising from the body of the anchor at the rear of the hook portion, as indicated.

I have accordingly produced an improved rail anchor of the type operating with a torsional resilient action wherein the one end of the anchor is firmly secured in its vertical position by a simple angular displacement of a portion of the body, thereby effecting a substantial economy of metal and further affording additional important advantages including the relatively increased resilient pressures obtained per unit of adjustment of the opposite end and the increase of effective angularity permitted incident to the improved form. The angular displacement of the vertically secured end portion of the bar further produces the desired offsetting of the related jaw member with relation to the major portion of the bar body thereby eliminating the requirement of a special bending operation to effect this result. Also, and as will be readily appreciated, while I have herein described and shown the resilient distortion of the bar for obtaining spring action as occurring within the straight body portion of the bar, this distortion may to a greater or less degree occur within that portion of the bar end comprising the jaws without sacrifice of the important advantages of my improved design. It is accordingly intended in the claims that reference to the distortion of the bar ends shall be broadly interpreted to comprehend either of the conditions referred to.

Having described my invention, I claim:

1. A rail anchor comprising a bar and jaws thereon adapted to engage the flanges at the opposite sides of a rail and adapted for gripping the rail flange under resilient distortion of the bar at one end with relation to the opposite vertically secured end portion, said latter end portion being formed for securing engagement by angularly disposing a portion of the bar to have longitudinally extended bearing engagement with the under side of the rail flange to co-act with its re-

lated jaw to secure its end of the bar in fixed vertical position with relation to the rail.

2. A rail anchor comprising a bar and jaws thereon adapted to engage the flanges at the opposite sides of a rail and adapted for gripping the rail flange under resilient distortion of the bar at one end with relation to an opposite vertically secured end portion, said latter end portion being formatively adapted for securing engagement by angularly disposing a portion of the bar to have longitudinally extended bearing engagement with the underside of the rail flange to co-act with its related jaw to secure its end of the bar in fixed vertical position with relation to the rail, said angularly disposed portion of the bar extending beneath the rail flange a substantial distance thereby to confine the distortion of the bar to a limited length thereof.

3. A rail anchor comprising a bar and jaws thereon adapted to engage the flanges at the opposite sides of a rail and adapted for gripping the rail flange under resilient distortion of the bar at one end with relation to an opposite vertically secured end portion, said latter end portion being formatively adapted for securing engagement by angularly disposing a portion of the bar to have longitudinally extended bearing engagement with the underside of the rail flange to co-act with its related jaw to secure its end of the bar in fixed vertical position with relation to the rail, said angularly disposed portion of the bar being joined to the remainder body portion by a curved junction portion.

4. A rail anchor comprising a bar and jaws thereon adapted to engage the flanges at the opposite sides of a rail and adapted for gripping the rail flange under resilient distortion of the bar at one end with relation to an opposite vertically secured end portion, said latter end portion being formed for securing engagement by angularly disposing an end portion of the bar to have longitudinally extended bearing engagement with the under side of the rail flange and to effect the offsetting of its jaw to one side of the bar body portion and said opposite end portion of the bar body being substantially straight with its jaw member bent in angular relation thereto to the opposite side of the bar body with relation to the co-acting jaw.

5. A rail anchor comprising a bar and jaws thereon adapted to engage the flanges at the opposite sides of a rail and adapted for gripping the rail flange under resilient distortion of the bar at one end with relation to an opposite vertically secured end portion, said latter end portion being formed for securing engagement by angularly disposing the end portion of the bar to have longitudinally extended bearing engagement with the under side of the rail flange and to

effect the offsetting of its jaw to one side of the major body portion at the opposite end and said latter end portion of the bar being substantially straight with its jaw member bent into angular relation thereto to the opposite side of body major portion with relation to the first jaw and said end portions being formed with opposed shoulder portions positioned to engage the edge surfaces of the rail flanges.

6. A rail anchor comprising a bar and jaws thereon adapted to engage the flanges at the opposite sides of a rail and adapted for gripping the rail flange under resilient distortion of the bar at one end with relation to an opposite vertically secured end portion, said latter end portion being formed for securing engagement by angularly disposing an end portion of the bar to have longitudinally extended bearing engagement with the under side of the rail flange and to offset its jaw to one side of the bar body portion and said first or major portion of the bar body portion having its jaw member bent into angular relation thereto to the opposite side of the bar with relation to the other jaw and having its jaw member of a form for operatively engaging the rail flange for self-mounting of the flange upon movement of the anchor from an angular position toward a position transverse of the rail.

7. A rail anchor comprising a bar and jaws thereon adapted to engage the flanges at the opposite sides of a rail and adapted for gripping the rail flange under resilient distortion of the bar at one end with relation to an opposite vertically secured end portion, said latter end portion being formed for securing engagement by angularly disposing an end portion of the bar to have longitudinally extending bearing engagement with the under side of the rail flange and said non-vertically secured end portion of the bar having its jaw member bent into angular relation thereto to the opposite side of the bar with relation to the other jaw and having its jaw member formed at its under side with an upwardly inclined entry surface adapted to have engagement with the rail flange for lifting said jaw upon the flange upon movement of the bar end longitudinally of the rail.

8. A rail anchor comprising a bar and jaws thereon adapted to engage the flanges at the opposite sides of a rail and adapted for gripping the rail flange under resilient distortion of the bar at one end with relation to an opposite vertically secured end portion, the jaw member at one end being offset with relation to the bar to one side thereof and the jaw at the opposite end being offset to the opposite side of the bar and one of said jaws being formed at its under side with an upwardly inclined entry surface adapted to have engagement with the rail

flange for lifting said jaw upon the flange upon movement of the bar end longitudinally of the rail.

9. A rail anchor comprising a bar and jaws thereon adapted to engage the flanges at the opposite sides of a rail and adapted for gripping the rail flange under resilient distortion of the bar at one end with relation to an opposite vertically secured end portion, the jaw member at one end being offset with relation to the bar to one side thereof and the jaw at the opposite end being offset to the opposite side of the bar, said bar being formed with opposed shoulder portions positioned to engage the edge surfaces of the rail flanges and one of said jaws being formed at its under side with an upwardly inclined surface adapted to have engagement with the rail flange and operative for lifting said jaw upon the rail flange upon movement of its end portion of the bar longitudinally of the rail.

10. A rail anchor comprising a bar and jaws thereon adapted to engage the flanges at the opposite sides of a rail and adapted for gripping the rail flange under resilient distortion of the bar at one end with relation to the opposite vertically secured end portion, said latter end portion being formed for securing engagement by angularly disposing a portion of the bar to have longitudinally extended bearing engagement with the under side of the rail flange to co-act with its related jaw to secure its end of the bar in fixed vertical position with relation to the rail, the bar ends being formed with opposed shoulders positioned to engage the rail flange edge surfaces and the vertically secured end portion being formed with a cut-away portion immediately beneath the rail flange edge portion providing clearance therefor.

11. A rail anchor comprising a bar and jaws thereon adapted to engage the flanges at the opposite sides of a rail and adapted for gripping the rail flange under resilient distortion of the bar at one end with relation to the opposite vertically secured end portion, said latter end portion being formed for securing engagement by angularly disposing a portion of the bar to have longitudinally extended bearing engagement with the under side of the rail flange to co-act with its related jaw to secure the end of the bar in fixed vertical position with relation to the rail, the bar ends being formed with opposed shoulders positioned to engage the rail flange edge surfaces, the vertically secured end portion being formed with a cut-away portion immediately adjacent the rail flange edge portion to provide clearance therefor, the opposite end portion of the bar having its jaw bent into offset relation to the bar body and formed with an upwardly

inclined under edge surface adapted to engage the rail flange to exert a lifting force upon the jaw upon movement of the bar end from an angular position toward a transverse position with relation to the rail.

12. A rail anchor comprising a bar and jaws thereon adapted to engage the flanges at the opposite sides of a rail and adapted for gripping the rail flange under resilient distortion of the bar at one end with relation to an opposite vertically secured end portion, said latter end portion being formed for securing engagement by angular displacement of the end portion of the bar to have longitudinally extended bearing engagement with the under side of the rail flange and the non-vertically secured end portion being substantially straight and provided with an angularly disposed jaw adapted to have overlying engagement with the rail flange and formed with a depending shoulder positioned to engage with the rail flange edge surface.

13. A rail anchor comprising a bar and jaws thereon adapted to engage the flanges at the opposite sides of a rail and adapted for gripping the rail flange under resilient distortion of the bar at one end with relation to an opposite vertically secured end portion, said latter end portion being formed for securing engagement by angular displacement of the end portion of the bar to have longitudinally extended bearing engagement with the underside of the rail flange and the nonvertically secured end portion being provided with a jaw positioned to have overlying engagement with the rail flange and having its end portion at its underside upwardly inclined to produce a lifting action upon movement of the bar end longitudinally of the rail and formed with a depending shoulder positioned to engage with the rail flange edge surface.

14. A rail anchor comprising a bar and jaws thereon adapted to engage the flanges at the opposite sides of a rail and adapted for gripping the rail flange under resilient torsional deflection of the bar, said bar having a portion thereof deformed to limit the resilient deflection to a reduced length of the bar body, substantially as described.

15. A rail anchor comprising a bar and jaws thereon adapted to engage the flanges at the opposite sides of a rail and adapted for gripping the rail flange under resilient torsional deflection of the bar, said bar having a portion thereof formed to limit the resilient deflection of the bar body to a length substantially less than the width of the rail base flange.

Signed at New York city, in the county of New York and State of New York this 4th day of April, A. D. 1927.

CHARLES FIELD YARDLEY.
